UNITED STATES PATENT OFFICE.

LEAMON G. SOUDER, OF PHILADELPHIA, PENNSYLVANIA.

MOVING SPIRAL STAIRWAY OR ELEVATOR.

SPECIFICATION forming part of Letters Patent No. 723,325, dated March 24, 1903.

Application filed March 24, 1902, Serial No. 99,594. (No model.)

To all whom it may concern:

Be it known that I, LEAMON G. SOUDER, a citizen of the United States, residing at the city of Philadelphia, in the county of Philadelphia and State of Pennsylvania, have invented certain new and useful Improvements in Moving Spiral Stairways or Elevators, of which the following is a specification.

My invention has relation to a moving stairway or elevator, and in such connection it relates more particularly to an improvement upon that type of stairway or elevator illustrated and described in Letters Patent No. 625,905, granted to me under date of May 30, 1899, the improvement residing in so constructing and arranging the parts of the stairway that the steps may ascend or descend in a spiral, thus forming a moving spiral stairway or elevator.

The principal objects of my present invention are, first, to provide a spiral stairway or elevator wherein the treads and risers constituting the steps of the stairway are flexed at right angles to each other when the steps ascend and descend, and the steps when so flexed travel in a spiral path either in ascending or descending, or both, and said treads and risers flexing into the same plane while changing from an ascending to a descending flight, or vice versa, and, second, to provide in conjunction with such a moving spiral stairway or elevator a landing-block at each floor traveled by the stairway, said block being of peculiar construction and arrangement so that the passenger may readily enter or leave the steps of the stairway while the stairway is in motion.

The nature and scope of my invention will be more fully understood from the following description, taken in connection with the accompanying drawings, forming part hereof, in which—

Figure 1 is a front elevational view, partly broken away and sectioned, of a double spiral moving stairway or elevator embodying main features of my invention. Fig. 2 is a horizontal sectional view of the same, the section being taken on the line 2 2 of Fig. 1. Fig. 3 is a top or plan view, enlarged and partly broken away, of the treads or risers when flexed into a horizontal plane. Fig. 4 is a longitudinal sectional view taken on the line 4 4

of Fig. 3. Fig. 5 is an enlarged vertical sectional view of a portion of one of the spiral stairways. Fig. 6 is an enlarged detail view 55 of the guide-rail projected upon a flat surface, showing the means for flexing the risers into the same plane as the treads of the steps. Fig. 7 is a cross-sectional view taken on the line 7 7 of Fig. 6. Fig. 8 is a perspective view, 60 enlarged, of one of the spiral staircases, a landing or floor, and a landing-block on the floor; and Fig. 9 is an interior view of the landing-block projected upon a flat surface.

In the drawings the stairway or elevator is 65 illustrated as double—that is to say, there is at the right hand of Figs. 1 and 2 an ascending spiral stairway or elevator and at the left hand of said figures a descending spiral stairway or elevator. It is, however, obvious that 70 but one of these stairways or elevators need be used; but for the sake of economy and convenience it will be found that the double stairway or elevator is preferable.

Referring to the drawings, each staircase 75 is provided with an outer spiral rail a and an inner spiral rail a' , these two rails forming the track upon which the steps of the stairway or elevator travel. As clearly indicated in Fig. 5, these rails a and a' are preferably supported upon brackets a^2 . At the upper and lower end of the stairway the spiral rails a and a' terminate in circular rails a^3 , arranged in a horizontal plane, and in plan they are approximately circular. The 85 steps of the stairway consist of alternate treads b and risers b' . The construction and arrangement of these treads and risers are indicated clearly in Figs. 3 and 4 and are substantially the same as the construction and 90 arrangement of the treads and risers illustrated in my previous patent, No. 625,905. The tread b is, however, segmental shaped in plan and is recessed to receive the wings d , which are pivoted, as at d' , intermediate 95 of the ends in the tread, so as to oscillate in the recess of the tread. The risers b' are each connected by the side plates b^2 to pins d^2 on the inner and outer perimeters of adjacent wings d . The pins d^2 and the pivot 100 d' are arranged in the same line or plane. Each tread b carries at its outer perimeter a roll or wheel b^3 , riding on the outer rail of the trackway a^3 and on the outer rail a of the

spiral trackway, and it also carries at its inner end a roll or wheel e^2 , working in vertical grooves e' of a vertically-disposed drum e . The outer perimeter of each riser b' also 5 has a roll or wheel d^3 riding on the outer of the rails a^3 and the outer spiral rail a . On the under face of each tread b is formed a bearing or bracket b^4 , in which is supported a wheel b^5 , riding on the inner rail a' of the 10 spiral trackway and on the inner of the horizontal rails a^3 , as clearly illustrated in Fig. 5. These wheels b^5 not only serve as guides for the inner perimeter of the treads, but also as supports to maintain the treads in horizontal position at all points on the stairway. 15 The wheels or rolls d^3 on the risers b' are preferably of less width than the wheels b^5 of the treads b , although both wheels are preferably of the same diameter. This difference in 20 widths of the wheels b^5 and d^3 forms one part of the means for flexing the riser b' into either right-angled relationship to the tread when the steps are formed on the spiral portion of the stairway or into horizontal relationship to the tread when the landings are 25 reached. The other and coacting portion of this means resides in the formation of a channeled guideway f (see Figs. 6 and 7) at the parts of the stairway where the spiral and horizontal portions merge. This guideway f has on 30 its interior a main groove f' , on the upper edge of which all the wheels b^5 and d^3 are normally adapted to travel. At a point slightly in advance of where the flexing of the riser is to take 35 place there is formed in the way f an auxiliary wedge piece or projection f^2 , which is thick enough to only permit the rolls or wheels d^3 to enter and to ride on the upper face of the main groove f' , while the other wheels b^5 are 40 forced to ride over the wedge-piece, as clearly illustrated in dotted lines in Fig. 6. By thus permitting the wheels d^3 to enter and ride on the upper surface of the groove f' while the wheels b^5 are forced to ride over the wedge- 45 piece the necessary flexures of the risers and treads into either step-sections or into the same horizontal plane are accomplished. This mechanism is substantially similar to corresponding mechanism illustrated in my former 50 patent, No. 625,905, and operates in substantially the manner described in said patent.

The means for positively driving the treads and risers of the stairway comprises, preferably, an endless band or rope g . This rope 55 or band g travels spirally up one staircase and down the complementary staircase where two stairways are used, as in Figs. 1 and 2. To enable the rope or band g to grip the treads and risers, the exterior wheels b^5 and 60 d^3 are each provided with a stationary shaft having an enlarged head g' , in which are formed two grooves g^2 and g^3 , diagonally crossing each other. When the steps are drawn upward in the spiral, the rope or band g sinks 65 into the grooves g^2 of the shafts on the treads and risers, and when the steps are drawn downward the band or rope g sinks into the

other grooves g^3 . The rope or band g is propelled by the following preferred mechanism: The main driving-shaft h is arranged vertically midway between the two spirals of the 70 staircase and is driven from a gear-wheel h' by mechanism. (Not shown.) At or near its upper and lower ends it is provided with a drum h^2 and a drum h^3 , around which the rope 75 or band g is passed, as illustrated in Fig. 1. The band or rope g is guided in proper relationship when not engaging the steps of the staircase by a series of guide sheaves or rollers h^4 . The vertically-grooved drums e , in 80 which the inner wheels e^2 of the treads b travel, are also caused to revolve at a speed required by the travel of the stairs by the following preferred means: The central driving-shaft h is provided with an upper and lower 85 gear-wheel m , each of which gears with the gear-wheels m' , fixed to a vertical shaft m^2 , carrying a drum e . As the shaft h rotates to move the band or rope g , and consequently the steps of the stairway, the drums e rotate 90 correspondingly to guide the inner ends of the treads up or down and around in a spiral direction.

When the stairway travels up or down through three or more floors without intermediate flexing of the steps into a horizontal plane, there may be arranged at intermediate floors a landing by means of which the passenger may enter or leave the stairway while the steps are traveling up or down spirally in 95 the stairway. A preferred form of such a landing is illustrated in Figs. 8 and 9 of the drawings, and it consists, essentially, in building up from the floor n of the structure a 100 block n' , having the following contour or 105 shape. The inner edge n^2 of this block n' follows the spiral line drawn through the outer corners b^{10} of the treads b , and the block slopes gradually upward and downward from that line away from the stairway until it merges 110 into the floor n . The block n' thus forms virtually a spiral continuation of the stairway leading tangentially from the outer edge of the steps to the floor, and thus ingress or 115 egress to or from the stairway is made easy and convenient. If but one stairway is desired, it is obvious that the band or rope g may travel either downward or upward when not in connection with the steps over suitable 120 guiding sheaves or rollers, and the treads and risers can likewise travel on the return flexed into a single plane to the point where the stairway begins to be formed.

Having thus described the nature and objects of my invention, what I claim as new, 125 and desire to secure by Letters Patent, is—

1. An elevating - conveyer of risers and treads forming a belt, having inclined spiral portions wherein the risers and treads are flexed into steps to form carrying-sections for 130 the load and having other portions wherein both risers and treads are flexed into a horizontal plane.

2. In an elevating conveyer or stairway

having horizontal and spirally-inclined portions, a band, comprising alternate risers and treads and constructed at all points throughout its length for the support of the load and 5 combined with means for causing the flexure of the risers and treads along the spiral portions into step-like carrying-sections.

3. In an elevating conveyer or stairway having horizontal and spirally-inclined ways, 10 a series of risers and treads hinged together, means on the horizontal ways for keeping the risers and treads in alinement, and means on the spiral ways for flexing the risers and treads into step-like carrying-sections.

15 4. In a spiral elevator or moving stairway, a series of risers and treads hinged together, means for flexing the risers and treads into a horizontal plane at the beginning and end of the stairway, and means for flexing the risers 20 and treads into steps along the spiral course of the stairway.

5. A spiral elevator or moving stairway, consisting of a chain of successive links pivoted together and forming a continuous 25 surface, combined with means for changing the angle of certain of the links with respect to alternate links whereby the chain may form either a horizontal traveling platform or a series of steps traveling along a spiral course.

30 6. In a spiral elevator or moving stairway, an endless chain of successive risers and treads hinged together combined with means for flexing the risers and treads into a horizontal plane at the beginning of the stairway, 35 means for flexing the risers and treads into steps, means for elevating the steps along a spiral course, means for flexing the risers and treads into a horizontal plane at the top of the stairway, means for thereafter flexing the

risers and treads into steps, and means for 40 lowering the steps so formed along a second spiral course.

7. In a spiral elevator or moving stairway, a series of risers and treads, means for flexing the same into step-like sections along a 45 spiral way, and a landing-block located intermediate of the ends of the spiral way and forming a spiral continuation of the spiral way and leading tangentially away from the outer edge of the step-sections. 50

8. An elevating-conveyer of risers and treads forming a belt having spiral portions wherein the risers and treads are flexed into steps to form carrying-sections for the load and having other portions wherein both risers 55 and treads are flexed into a horizontal plane, said load-carrying sections adapted to travel spirally up or down on an incline, a central support around which the load-carrying sections travel in their spiral course, said central support being arranged at one edge of the load-carrying sections and adapted to guide the same vertically in their travel. 60

9. An elevating-conveyer wherein the load-carrying sections travel spirally upward during one part of the course and spirally downward during another part of said course, two separate and distinct central supports, the load-carrying sections traveling around one of said supports in ascending and around the 70 other in descending.

In testimony whereof I have hereunto set my signature in the presence of two subscribing witnesses.
